Attorney

UNITED STATES PATENT OFFICE.

VICTOR ZIMMERMAN, OF HOLYOKE, MASSACHUSETTS.

GAME.

Application filed November 30, 1926. Serial No. 151,776.

The present invention relates to a game having for its principal object to afford healthy out-of-door exercise, particularly for children wherein the necessary implement 5 for playing the game may be manufactured at a very low cost.

Another important object of the invention lies in the provision a game which when played will entail the use of sufficient skill 10 to maintain the interest and which will afford considerable amusement and pleasure.

Another very important object of the invention is to provide a very simple and inexpensive racket which is light, durable, and 15 otherwise well adapted to the purpose for which it is designed.

Another object of the invention is to provide an improved missile which is inexpensive to manufacture, and of a light harmless 20 formation so that if one of the players is struck thereby, no injury will be imparted.

With the above and numerous other objects in view as will appear as the description proceeds, the invention resides in certain novel features of construction, and in the combination and arrangement of parts 25 as will be hereinafter more fully described and claimed.

In the drawing:—

Figure 1 is a perspective view of a racket and missile used in the game.

Figure 2 is a section through the handle portion of the racket, and

Figure 3 is a sectional view through the 35 missile.

Referring to the drawing in detail it will be seen that the game consists generally of two or more rackets for two or more players and a single missile, and the idea is to maintain the missile in the air, it being struck first by one player and then the next player, and so forth.

Playing the game in this manner will give the players considerable light healthy exercise in a harmless manner with practically no danger of injury to the players.

The racket comprises a bow or curved frame 5 having spaced parallel extremities 6 fixed to opposite sides of a filler bar 7. These 50 extremities 6 are preferably fixed in place on the bar 7 by screws 8, although other suitable fastening elements may be used. The

bow 5 is constructed preferably of wood, and is bent into the formation shown and described by any suitable wood bending process.

The stringing 9 in the bow or frame portion 5 has its various runs cross each other to form squares and the runs are all disposed obliquely to the bar and extremities 6. The 60 bar 7 and the extremity 6, of course, forms the handle of the racket. A hook 10 extends from the end of the bar 7 a slight distance into the bow or frame portion 5 so that two of the runs of the stringing 9 may be threaded therethrough to maintain them in parallelism and at right angles to the remaining runs as is necessary in starting and finishing the stringing.

The numeral 11 denotes a spherical ball 70 which is constructed of cork, and is provided with a recess 12 in the periphery thereof into which is screwed a weight element 14 in the form of an ordinary wood screw, so that the head thereof is countersunk and cannot do 75 any injury in case the missile should strike some one. Three feathers 15 are stuck into the ball 11 on the opposite side from the screw weight element 14 and are arranged in a triangular manner.

The novelty of my improved device lies particularly in the construction of the racket and in the construction of the missile. It will be seen that these two parts of the game may be constructed very cheaply and are 85 light, yet strong and durable to withstand the usages contemplated. Thus the game may be placed on the market at a very low cost so as to be accessible to a large number of children.

It is thought that the construction, utility, and advantages of the game and parts thereof will be clearly understood by those skilled in this art without a more detailed description thereof. The present embodiment of the invention has been disclosed in detail merely by way of example since in actual practice it attains the features of advantage enumerated as desirable in the statement of the invention and the above description. It will 95 be apparent that changes in the details of construction, and in the combination and arrangement of parts may be resorted to without departing from the spirit or scope of

the invention as hereinafter claimed or sacrificing any of its advantages.

Having thus described the invention, what I claim as new is:—

- 5 A racket comprising a bowed frame terminating in straight parallel spaced extremities, a filler bar between the extremities, co-

extensive therewith and fixed thereto, stringing in the bowed frame, and a hook on one end of the bar and extending into the bowed frame to engage portions of the stringing.

In testimony whereof I affix my signature.

VICTOR ZIMMERMAN.
